UNITED STATES PATENT OFFICE.

JAMES LAKE, JR., OF NEW YORK, N. Y.

HAT-PRESSING MACHINE.

1,126,492.

Specification of Letters Patent.

Patented Jan. 26, 1915.

Application filed July 17, 1914. Serial No. 851,562.

To all whom it may concern:

Be it known that I, JAMES LAKE, Jr., a citizen of the United States, and a resident of the city of New York, borough of Brooklyn, in the county of Kings and State of New York, have invented a new and improved Hat-Pressing Machine, of which the following is a full, clear, and exact description.

Among the principal objects which the present invention has in view are: to provide means for shaping hat crowns under pressure, the pressure being applied to the crown independently of the brim; to provide for contracting the crown within the desired compass and disposing the surplusage within the area usually covered by the hat band, to be in service concealed thereby; and to provide means for distributing the compression area over a greater surface of the crown.

Drawings.—Figure 1 is a side view of a machine constructed and arranged in accordance with the present invention; Fig. 2 is a front view thereof; Fig. 3 is a vertical section taken as on the line 3—3 in Fig. 2; Fig. 4 is a detail view, on an enlarged scale and in vertical section taken on the median line, showing the press as partially closed to shape the brim of a hat; Fig. 5 is a similar view, showing the press completely closed to shape the crown of the hat.

Description.—As seen in the accompanying drawings, the press is provided with a heating table 10 and a die plate 11. Said table and die plate are furnished with heating means embodying annular chambers 12, through which steam is circulated by pipes 13, as in machines of conventional construction. The table 10 has a subtended cylinder 14 to operate as a guide for the crown block 15 and to form a housing for a plunger head 16. The plate 10 and cylinder 14 thereof are supported in service by an operating table 17.

The plunger head 16 is hollowed to form a heating chamber, which is supplied with steam by means of pipes 18, which enter below said plunger, extending upward through the table 17. The head 16 is operatively connected with a short pitman 19 having a circular opening or hollow 20 to fit an eccentric disk 21. The disk 21 is fixedly mounted on a rocking shaft 22, at the outer end whereof is rigidly mounted a power lever 23. The lever 23 is suitably provided with bearings in the lower end of a raceway 24, as

shown best in Fig. 3 of the drawings. It is to avoid the raceway 24 that I have provided the drop-centered framing bar 25.

The framing bar 25 is rigidly connected with the lower ends of laterally-disposed plungers 26. Said plungers are extended upward through passages formed in standards 27, and have each at the upper end thereof screw-threaded sections to engage adjusting nuts 28, by which the die plate 11 is set in operative position, the same being provided with laterally-disposed bored bearing boxes 29.

The construction embodying the bar 25, plungers 26 and die plate 11 constitutes a reciprocating frame, the purpose of which is to raise and lower the plate 11 to and from the table 10 to introduce a die head 30 within the crown block 15, and to overlie a brim die 31 on the brim block 32. The movement of said frame is primarily imparted thereto by the operation of the rocking shaft 33. The shaft 33 is operatively connected with the framing bar 25 by arms 34 and links 35. The shaft 33 has reduced ends 36 mounted in bearings formed in lugs 37. The arms 34 and links 35 connected therewith are normally elevated by springs 38, for which purpose said arms are connected by a tie rod 39, as seen best in Figs. 2 and 3 of the drawings. The arms 34 are lowered when the foot lever 40 is depressed. The foot lever 40 is pivoted on a shaft 41, which is mounted in bearings in a bracket 42. The foot lever 40 is connected by means of a link 43 with a lug 44 formed integrally on the shaft 33.

From the foregoing it will be seen that when the operator, by placing his foot upon the lever 40, depresses the same, the shaft 33 is rocked; the free ends of the arms 34 and the links 35 connected therewith are depressed to lower the framing bar 25 and the plungers 26 connected therewith. The plate 11 having been adjusted on the plungers 26, the movement described draws said plate and the brim die plate 31 down to rest firmly on the brim block 32, to clamp a brim A of a hat previously placed on said block.

To hold a brim die plate and frame connected therewith in the above-described position during the subsequent operation of the machine, hooks 45 are employed. The hooks 45 are provided at the lower ends thereof with eccentric collars fitting eccentric disks 46 mounted on a rectangular rocking shaft 46. The shaft 46 is rigidly provided with tabbed

disks 47, the tabs 48 whereof form stop members for lugs 49. The lugs 49 are extended from the sides of the hooks 45, and are engaged by the tabs only when the power lever 50 is thrown back to the inactive position, the object of the tabs 48 and lugs 49 being to disengage the hooks 45 to release the framing bar 25 and frame connected therewith, above which framing bar the hooks 45 are thrown when the power lever 50 is drawn toward the front of the machine, in the active position thereof. The hooks 45 are each provided with a counterweight 51, the operation of which is to rock said hooks forward until arrested by the framing bar 25, the power lever 50 and eccentric disks mounted thereon being further revolved to impart a downward pull upon said hooks 45, the bar 25 and frame connected therewith including the plate 11. In this manner, there is imparted to the brim die plate 31, power to press and set the brim of the hat being formed prior to and independent of the pressure which is imparted to the crown of the hat.

When using a machine constructed and arranged in accordance with the present invention, the pressed crown may be of any desired shape. This is regulated by the inner shape of the block 15, which may be varied indefinitely. The same is true also of the brim, the block 32 being also varied to accommodate the style or demand of the trade. The crown block 15 is mounted to slide in the brim block 32, as shown best in Figs. 4 and 5 of the drawings.

The block 32 is preferably cylindrical. The upper portion is reduced to form a thin edge 52, likewise cylindrical externally to fit a bore with which the brim block 32 is provided. Said bore in the block 32 is driven to form a shoulder 53, said shoulder being located at a point coincident with the area covered by the sweat-band of the finished hat. The gap between the shoulder 53 and the thin edge 52 is covered by a thin metal band 54 when the blocks are brought together, the upper part of said thin edge extending between the surface of the bore in the brim block and said metal band 54. The insertion of the edge in the manner referred to occurs prior to pressure being applied to the die head 30. The thin metal band 54 is thus reinforced prior to lateral pressure being exerted thereon by the pressure applied to the die head 30.

After the setting pressure has been applied to the brim in the manner as above described, and after the die head 30 has been introduced into the crown mold in the crown block 15, pressure is applied to the crown by lifting the block 15. The die head 30 is of conventional construction and adapted for molding to the shape within which it is confined. The block 15 is raised when the

eccentric disk 21 is rotated to lift the pitman 19 and plunger head 16 carried thereby. This occurs when the power lever 23 is lifted from the position shown best in Fig. 2 of the drawings, to the opposite side of the machine. It will be noted that as the block 15 is lifted, the pressure applied to the crown is uniform throughout the body of the crown. It will also be noted that the take-up or lap incident to the compression of the material of the crown falls within the area covered by the straight portion coincident with the metal band 54.

In straw hats particularly, it is desired that the compression incident to shaping and setting of the crown should be concealed or disguised. This, in the present case, is provided for by locating the lap in the above-designated area, which, in the finished hat, is covered interiorly by the sweat-band and exteriorly by the ribbon or hat-band with which hats of this character are generally provided.

From the foregoing, it will be seen that by employing crown blocks such as 15 and brim blocks such as 32, the crown and brims may be independently varied and used with a variety of other and corresponding blocks. Further, it will be observed that the blocks 15 being all cylindrical, irrespective of the shape or size of the crown of the finished hat, a large variety of said blocks may be rapidly and readily introduced or placed in the machine, with considerable saving of time over that required when employing the present methods and machines.

Claims:

1. A machine as characterized, comprising a stationary brim block; a movable crown block slidably mounted in said brim block and normally spaced apart therefrom; a brim die plate for clamping upon said brim block; a crown die head extensible within, to fill said crown block; means for forcing said die plate and said die head in clamping relation to their respective blocks; and means for moving said crown block toward said brim block in pressing relation to said die head.

2. A machine as characterized, comprising a stationary brim block; a movable crown block slidably mounted in and spaced apart from said brim block, the line of separation being adjacent the surface of said brim block, said crown block being internally shaped to the form of a hat crown; a brim die plate; an inelastic-fluid die head for insertion within said crown block; means for forcing said brim die plate on said brim block; and power means for moving said crown block upon said die head and toward said brim block.

3. A machine as characterized, comprising a stationary brim block; a movable crown block slidably mounted in and spaced

- apart from said brim block, the line of separation being adjacent the surface of said brim block, said crown block being internally shaped to the form of a hat crown; a
5 brim die plate; an inelastic-fluid die head for insertion within said crown block; means for forcing said brim die plate on said brim block; a heating plunger head for said crown block; and means for forcing said
10 heating plunger head and crown toward said brim block, said means embodying a rocking shaft, a power lever therefor, an eccentric, and a pitman pivotally connecting said cam and said plunger head.
15 4. A machine as characterized, comprising a brim block; a crown block having an interior recess shaped to form a crown die; a die member to independently clamp a hat
brim and crown upon their respective blocks; and means for moving said crown 20 block toward said brim block subsequent to application of full pressure thereto.
5. A machine as characterized, comprising a brim block; a crown block having a recess shaped to form a substantially complete crown; dies coöperating with said blocks; and means for moving said blocks into closer relation while said blocks are both under pressure.
In testimony whereof I have signed my 25 name to this specification in the presence of two subscribing witnesses.
